ABSTRACT OF THE DISCLOSURE

Hydroalkylation of mononuclear hydrocarbons is effected under controlled conditions to yield product hydroalkylate with minimum formation of undesired by-products.

BACKGROUND OF THE INVENTION

This invention relates to hydroalkylation. More specifically it relates to the selective hydroalkylation of benzene to permit attainment of high yields of cyclohexylbenzene.

As is well known to those skilled in the art, it is possible to hydroalkylate aromatic, preferably mononuclear, hydrocarbons such as benzene, by the reaction with hydrogen in the presence of hydroalkylation catalyst under hydroalkylation conditions to yield product hydroalkylate. This product primarily contains cyclohexylbenzene and the ortho-, meta-, and para-isomers of dicyclohexylbenzene.

It is an object of this invention to provide a process for hydroalkylation. It is another object of this invention to provide a process for hydroalkylating a charge benzene to produce cyclohexylbenzene. Other objects will be apparent to those skilled in the art.

SUMMARY OF THE INVENTION

In accordance with certain of its aspects, the novel process of this invention for hydroalkylating a charge mononuclear aromatic hydrocarbon with a hydroalkylating quantity of hydrogen may comprise:

passing said charge hydrocarbon and a first portion of said hydroalkylating quantity of hydrogen through a first hydroalkylation operation at hydroalkylation conditions thereby forming a partially hydroalkylated stream;

withdrawing said partially hydroalkylated stream from said first hydroalkylation operation;

passing said partially hydroalkylated stream through at least one subsequent hydroalkylation operation at hydroalkylation conditions;

passing the remainder of said hydroalkylating quantity of hydrogen to said subsequent hydroalkylation operation;

maintaining said partially hydroalkylated stream, during passage into each hydroalkylation operation, at hydroalkylation conditions thereby forming a product hydroalkylate; and

withdrawing product hydroalkylate from the last of said hydroalkylation operations.

DETAILED DESCRIPTION OF THE INVENTION

The charge mononuclear aromatic hydrocarbons which may be hydroalkylated by the process of this invention may include benzenes, including substituted benzenes, such as benzene *se*, toluene, xylenes, etc. The preferred charge may be benzene *se*.

Hydroalkylation may preferably be effected in one embodiment by passing to the hydroalkylation operation a charge mononuclear aromatic hydrocarbon, typically benzene, together with recycled materials, typically dicyclohexylbenzenes. Among the latter may be ortho-di-

2

cyclohexylbenzene, meta-dicyclohexylbenzene, and para-dicyclohexylbenzene.

The charge which may be hydroalkylated by the process of this invention may include, in addition to fresh charge benzene, other components including cyclohexylbenzene, para-dicyclohexylbenzene, tricyclohexylbenzenes, etc. The composition of the total charge (ex hydrogen) entering the reactor may include:

	Components	Parts	Typical
10	Benzene.....	40-99.5	92.6
	Cyclohexylbenzene.....	0-5	0.6
5	Ortho-dicyclohexylbenzene] meta-dicyclohexylbenzene].....	0.5-15	5.2
	Para-dicyclohexylbenzene.....	0-15	1.6
15	Methyl cyclopentane.....	0-10	0
	Cyclohexane.....	0-15	0

Other components may be present, including methyl cyclopentyl benzenes, bicyclohexyl, tricyclohexyl benzenes, etc.

Preferably 100 parts by weight of benzene and a hydroalkylating quantity, preferably 0.21-10 parts, more preferably 0.2-3 parts, say 1.1 parts by weight of hydrogen may be employed for hydroalkylation.

25 Hydroalkylation may be effected in the presence of a hydroalkylation catalyst and a hydroalkylating quantity of hydrogen. The hydrogen need not be pure; but preferably hydrogen of 80%-100% purity may be used. The hydrogen should preferably be free of any impurities which may poison the catalyst. Hydrogen recovered from a reforming operation may be suitable.

30 The catalyst may contain a Group VIII transition metal component, e.g., cobalt, nickel, ruthenium, rhodium, palladium, iridium, and platinum. The preferred type of catalyst may include a Group VIII metal, typically nickel or cobalt; and it may also contain 0-30%, typically 10%-20%, say 19% of a Group VI metal, typically tungsten, on a silica-alumina catalyst support. When the Group VIII metal is Co or Ni, it will preferably be present in an amount of 2%-30%, typically 4.0%-25%, say 22%. When the Group VIII metal is a noble metal, it may be present in amount of 0.2%-5%, say 1%. Such a catalyst may be prepared for example by impregnating or ion-exchanging a commercial NH₄-exchanged Y zeolite catalyst with e.g. nickel nitrate (or cobalt nitrate) and thereafter with ammonium metatungstate solution and then drying the catalyst in air at say 100° C. The so-dried catalyst may be further dried at 150° C. and then calcined to a maximum temperature up to 800° C.

35 The catalyst may be calcined during which residual nitrates are decomposed and the catalyst is dehydrated. The catalyst may (preferably after loading into the hydroalkylation unit) be reduced in the presence of hydrogen for a minimum of 1 hour and typically at least 4-8 hours at a temperature preferably above about 300° C. and typically 300°-700° C., say 500° C.

40 The so-prepared typical catalyst may contain, on a dry basis, 6% nickel, 19% tungsten, and 22% hydrogen-Y zeolite, the remainder being amorphous silica-alumina support.

45 Hydroalkylation of aromatic feed may be effected by using this catalyst at an LHSV of 1.0-15, typically 2-10, say 3.

The pressure of hydroalkylation may typically be 100-65 1500 p.s.i.g., preferably 100-500 p.s.i.g., say 500 p.s.i.g.; at this pressure the reactants are maintained substantially in liquid phase—except for the hydrogen which is in gas phase.

70 It is a feature of the novel process of this invention that hydroalkylation be carried out in a plurality of (including a first and at least one subsequent) hydroalkylation operations or stages. Each operation may be carried

out in a separate portion of a single reaction vessel or, as is more preferred, in a separate reaction vessel. Typically there may be 2-10 separate hydroalkylation operations, commonly 2, each carried out in a separate reaction zone or vessel. The partially hydroalkylated effluent from the first hydroalkylation operation may be passed to subsequent hydroalkylation operations wherein additional hydrogen is admitted and further hydroalkylation may occur.

The amount of hydrogen admitted to the first reactor 10 may typically be greater than the amount calculated from the total amount of hydrogen added in all the hydro-alkylation operations divided by the number of hydro-alkylation operations.

In a preferred embodiment, hydroalkylation may be 15 carried out by passing the charge hydrocarbon and a first portion of the hydroalkylating quantity of hydrogen through a first hydroalkylation operation at hydroalkylation conditions. In one preferred embodiment, hydro-alkylation may be effected in two operations; and the 20 amounts of hydrogen admitted to each of the hydro-alkylation operations may be substantially equal.

Typically, however, when two stages are employed, the hydrogen admitted to the first hydroalkylation operation may be greater than about 50%, e.g. 50%-70%, say 25 55%, of the hydroalkylating quantity of hydrogen; and that admitted to the second hydroalkylation operation may be less than about 50%, e.g. 30%-50%, say 45%.

If hydroalkylation be carried out in three steps, the quantity of hydrogen admitted to the first zone may be 30 35%, say 40% of the total hydrogen admitted; the quantity admitted to the second zone may be 30%-35%, say 35% of the total; and the quantity admitted to the third zone may be 20%-30%, say 25%.

Typically the inlet temperature to the first operation 35 may be lower than the inlet temperature to subsequent operations; and consequently more hydrogen may be permitted to react in the first zone or operation without exceeding a preferred upper limit of temperature. Generally the fresh charge benzene is more reactive than is the 40 mixed hydroalkylation product; and thus a lower inlet temperature may be used in the first hydroalkylation operation.

It is a feature of the process of this invention that each 45 of the hydroalkylation operations be carried out at maximum operating temperature of less than about 250° C. (482° F.) and preferably at less than 210° C. (410° F.). Typically, temperature may be 100° C.-210° C., say 190° C. (375° F.) and the hydrogen partial pressure may be 50-1500 p.s.i.g., preferably 100-1500, more preferably 100-700 p.s.i.g., say 500 p.s.i.g.

The temperature of reaction may in one embodiment be controlled by cooling the feed to each hydroalkylation operation to a temperature of 20° C.-150° C., preferably 40° C.-100° C., say 80° C. below maximum operating 55 temperature. Thus the feed to a hydroalkylation operation may be at 80° C.-200° C., preferably 100° C.-190° C., say 125° C. As hydroalkylation occurs in one hydro-alkylation operation, the temperature rises within the operating temperature range.

In an alternative embodiment, each hydroalkylation operation may be carried out in a reactor which includes means for heat transfer. Cooling may be effected for example by passing the feed gases through a heat exchanger reactor wherein the reactants are cooled by indirect heat transfer against a cool heat transfer medium e.g., a gas which is cooled externally.

It has unexpectedly been found that practice of the process of this invention permits recovery of product containing decreased proportions of undesirable by-products, particularly when operating at lower temperatures. In a typical series of comparative runs, benzene may be hydroalkylated with hydrogen over a nickel-tungsten on a hydrogen form of zeolite Y catalyst (which catalyst is first reduced at 480° C. with hydrogen). It is found that, 70 75

as the average temperature of operation in each bed decreases from 200° C. (400° F.) to 120° C. (250° F.), the weight ratio in the product stream of undesired by-product methyl cyclopentane to desired by-product cyclohexane decreases from 2.0 to about 0.2; i.e. the composition of the product stream drastically changes from one containing only 33% desired by-product to one containing 83% desired by-product.

Similarly it is also found that impurities, which have boiling points within the cyclohexylbenzene range (and which would thus be expected to appear in the fractionated cut containing product cyclohexylbenzene) are substantially reduced. Specifically the ratio of such impurities to cyclohexylbenzene may typically be decreased from about 0.12 at 205° C. (400° F.) down to less than 0.01 at 120° C. (250° F.).

It will be apparent to those skilled in the art that results comparable to those noted may be achieved by the use of other catalyst systems.

As will be apparent, the composition of the hydro-alkylate product will be a function of the charge to the hydroalkylating operation. In one embodiment, wherein the charge benzene is benzene *se plus* recycle ortho-dicyclohexylbenzene, meta-dicyclohexylbenzene, and para-dicyclohexylbenzene, the product may typically contain the following:

TABLE

Component:	Preferred parts
Benzene	58.9
Cyclohexylbenzene	28
Ortho-dicyclohexylbenzene	5.4
Meta-dicyclohexylbenzene	5.4
Para-dicyclohexylbenzene	2.6
Methylcyclopentane	0.8
Cyclohexane	3.8
Dicyclohexyl and others	0.9

In the preferred embodiment, the hydroalkylate product in amount of 100 parts may be passed, in liquid phase, to a separation operation wherein any hydrogen present may be flashed off.

The flashed product liquid may be preferably heated and passed to a benzene recovery tower. Typically 58.9 parts of benzene may be recovered as overhead and condensed against water. A portion of the condensate is returned as pumped reflux to the benzene recovery tower; and the remainder of the recovered benzene may be recycled to the hydroalkylation operation, preferably after purification to remove e.g. C₆ naphthenes.

41.1 parts of bottoms may be heated and passed, in the preferred embodiment, to cyclohexylbenzene recovery tower. Overhead cyclohexylbenzene may be condensed against water; and a portion thereof may be returned as pumped reflux to the cyclohexylbenzene recovery tower.

Bottoms from the cyclohexylbenzene recovery tower, in amount of 8 parts, may be heated and passed in the preferred embodiment of the dicyclohexylbenzene recovery tower. Bottoms from the dicyclohexylbenzene recovery tower may typically include tricyclohexyl (and higher boiling) benzenes.

The overhead from the dicyclohexylbenzene distillation operation may include dicyclohexylbenzene; and typically this stream may include less than 10% of other components. It may be found that the dicyclohexylbenzene fraction recovered as overhead from the dicyclohexylbenzene distillation tower may contain 0.5-15 parts, say 2.6 parts of para-isomer and 0.2-15 parts, say 5.4 parts of the mixed ortho- and meta-isomers.

Typically 8.0 parts of the dicyclohexylbenzene fraction may be cooled to minus 20° C. to plus 25° C., say minus 10° C. There may be preferably added to the fraction, prior to cooling, 1.6-4 parts, say 2.4 parts of a diluent, typically a lower alkanol such as isopropyl alcohol or methanol. During cooling, the para-isomer may crys-

tallize and separate from the ortho- and meta-isomer which remain in the liquid phase. The cooled mixture, a slurry of the solid phase para-isomer in liquid phase containing the ortho- and meta-isomer and preferably diluent, may be passed to a separation operation, typically a filtration operation.

In the filtration operation, conducted at minus 20° C., plus 25° C., say minus 10° C., 0.2-10 parts, say 1 part, of crystals of para-dicyclohexylbenzene (containing typically 0.1-1 parts, say 0.2 parts of mixed ortho- and meta-) are separated as filters cake from the filtrate which contains 0.5-15 parts, say 5.2 parts of ortho- and meta-dicyclohexylbenzenes (and 0.1-4 parts, say 1.6 parts of para-) and optionally say 0.6 parts of cyclohexylbenzene.

The filter cake may be washed with lower alkanol, typically isopropanol and recovered therefrom as by further filtration. Yield of para-dicyclohexylbenzene (filter cake) may be 0.2-10 parts, say 1 part.

It is possible to carry out to the process of this invention by admitting to the hydroalkylation operation in the preferred embodiment 0.5-15 parts, say 5.2 parts of dicyclohexylbenzene, preferably non-para-dicyclohexylbenzenes. Preferably the dicyclohexylbenzene admitted to the hydroalkylation operation will contain less than 4 parts, typically 1.6 parts (more preferably it will contain as little as possible) of the para-isomer.

The stream of dicyclohexylbenzene admitted with charge benzene to the hydroalkylation operation may be essentially meta-dicyclohexylbenzene (in amount of 0.5-15 parts, say 5.2 parts) or, less preferably, ortho-dicyclohexylbenzene (in amount of 0.5-15 parts, say 5.2 parts).

The stream of dicyclohexylbenzenes admitted to the hydroalkylation operation may include 0.5-15 parts, say 5.2 parts of mixed ortho- and meta-isomers in amount substantially equal to the amount thereof formed during the hydroalkylation of benzene. In one embodiment, the dicyclohexylbenzene separated from the product hydroalkylate may, in whole or part, be recycled to the hydroalkylation reaction.

It will be apparent to those skilled in the art that the novel process of this invention permits hydroalkylation to be carried out at low temperatures in manner to yield high conversion to desired products, typically cyclohexylbenzene, with low yield of undesired naphthenes and of impurities boiling in the cyclohexylbenzene boiling range.

The use of intermittent addition of hydrogen, the hydroalkylation in the presence of large excesses of e.g. benzene, and the temperature control during hydroalkylation permit attainment of desired results.

DESCRIPTION OF PREFERRED EMBODIMENTS

Practice of the process of this invention may be apparent to those skilled in the art from inspection of the following examples wherein as elsewhere in this specification, all parts are parts by weight unless otherwise specified.

Examples I-III

In practice of the process of this invention according to one embodiment, hydroalkylation is effected by use of a catalyst, containing 6% nickel and 19% tungsten on silica-alumina support containing 22% of the hydrogen form of zeolite Y, which had been reduced by contact with hydrogen for 2 hours at 370° C. (700° F.) and 500 p.s.i.g. During hydroalkylation, benzene is admitted to the reactor together with 51% of the hydroalkylating quantity of hydrogen. At operating pressure of 500 p.s.i.g. (partial pressure of hydrogen), the nominal (inlet) temperature within the reactor is 190° C. (375° F.) and the temperature within the catalyst bed 188° C.-205° F. (370° F.-400° F.).

The product is collected over 63 hours; and it is then passed through the reactor a second time at inlet temperature of 188° C. (370° F.) with 49% of the hydroalkylating quantity of hydrogen. The product is col-

lected and analyzed; the following table sets forth the total parts of hydrogen added per pass per 100 parts of benzene, and also the composition, in terms of weight percent, of product collected (based upon benzene feed) after the first and after the second pass.

Component	I, first pass	II, second pass
Hydrogen added, parts	0.75	0.71
Methylcyclopentane, percent	1.1	2.0
Cyclohexane, percent	1.6	2.8
Cyclohexylbenzene impurities, ¹ percent	0.7	1.3
Cyclohexylbenzene, percent	15.8	28.4
Dicyclohexylbenzene impurities, ² percent	0.8	
Dicyclohexylbenzene, percent	3.2	8.6

¹ Impurities boiling in the cyclohexylbenzene boiling range.

² Impurities boiling in the dicyclohexylbenzene boiling range.

In a control reaction (III), benzene was hydroalkylated under comparable conditions with an inlet temperature of 190° C. (375° F.). The reaction which occurred raised the temperature to over 260° C. (500° F.). Under these conditions, 30%-45% of the benzene was consumed forming light gases and the product contained only 3.6 wt. percent of desired cyclohexylbenzene and 0.1 wt. percent dicyclohexylbenzene.

It is apparent that practice of the novel process of this invention permits attainment of results which are much superior to those obtained in the control Example III.

Examples IV-VIII

In a second series of comparative examples, hydroalkylation of benzene was carried out over a catalyst (the same as that of Ex. I-III) which had been reduced in a stream of hydrogen for 4 hours at 482° C. (900° F.). The charge benzene was dried by passage through silica gel and then over calcined 4A Zeolite (Linde molecular sieve); and it was charged at 2 LHSV together with deoxygenated hydrogen. All the hydrogen (0.88 parts of hydrogen per 100 parts of benzene) was consumed. Initial pressure was 400 p.s.i.g., but as the catalyst aged, the pressure rose to 500 p.s.i.g. Inlet temperature is 150° C. (300° F.) with a rise of 160 C. (30° F.) in the catalyst bed. The product is collected over 4-96 hours.

This product is then passed through the reactor a second time at 2 LHSV and inlet temperature of 150° C. (300° F.) together with hydrogen as before but with hydrogen in amount of 0.40-0.69 parts per 100 parts of benzene originally charged. Product from the second pass is collected in three aliquots: (a) 0-108 hours (Ex. V); (b) 108-116 hours (Ex. VI); and (c) 116-144 hours (Ex. VII). The following table sets forth the composition of the products collected, in terms of weight percent of product collected (based upon benzene feed) after the first pass and (a) after 108 hours, (b) 108-116 hours, and (c) 116-144 hours. Also showing is the total parts of hydrogen added per pass per 100 parts of benzene.

Component	First pass, IV	Second pass		
		0-108 h., V	108-116 h., VI	116-144 h., VII
Hydrogen added	0.88	0.39	0.68	0.66
Benzene	72.7	62.5	53.4	53.9
Methyl cyclopentane	0.15	0.27	0.23	0.24
Cyclohexane	2.87	4.44	5.37	5.23
Cyclohexylbenzene				
impurities	0.2	0.4	0.5	0.5
Cyclohexylbenzene	20.8	25.9	31.3	31.0
Dicyclohexylbenzene	3.3	6.8	8.9	9.0

It will be apparent from comparison of Example VII (at 150° C.) with Example II (at 188° C.) that in practice of this invention, operation at decreased temperature permits recovery of the desired cyclohexylben-

zene with decreased amounts of cyclohexylbenzene impurities (e.g. 0.5/31.0 or 1.6% v. 1.3/28.4 or 4.6%).

In a control reaction (VIII), benzene was hydroalkylated in comparable manner except that 100% of the hydroalkylating quantity of hydrogen (139 parts per 100 parts of benzene) was admitted to the single stage reactor. The inlet temperature was 150° C. (300° F.) and the temperature rose to over 220° C. (428° F.). The product stream after 28 hours was as set forth supra.

Comparison of typical Example VII of this invention with control Example VIII, which yields substantially the same cyclohexylbenzene content (31.0% v. 32.5%) reveals that in experimental Example VII, the undesirable cyclohexylbenzene impurities were substantially decreased by a factor of more than two (0.5/31.0 or 1.6% v. 1.1/32.5 or 3.4%) compared to control Example VIII; and the undesirable methylcyclopentane content was decreased by a factor of about 5 (0.24% v. 1.2%).

Examples IX-XI

In a third series of comparative examples, hydroalkylation of benzene was carried out over a catalyst comprising 22% cobalt dispersed on a rare earth exchanged zeolite Y catalyst that had been calcined at 800° C. in air and then reduced in the unit with a flow of hydrogen at 480° C. at atmospheric pressure. The benzene used was pretreated with sodium to remove all forms of oxygen-containing components and then pumped over calcined 4A molecular sieves at room temperature before entering the reactor. The benzene was charged at 2 LHSV together with deoxygenated hydrogen. All the hydrogen added was consumed and the rate of hydrogen addition was used to control the extent of the reaction. The pressure on the unit averages 250 p.s.i.g.

The unit was operated with an average 1.27 weight units of hydrogen added per 100 units of benzene. The hydrogen was completely consumed in the first few inches of the 12-inch depth bed of catalyst, based on the temperature rise across the catalyst bed. The inlet temperature averaged 115° C. with the maximum temperature averaging 205° C. The product is collected over a 38-hour period (Example IX).

In Example X, this product is then passed through the reactor a second time at 2 LHSV together with 0.83 units of hydrogen and an inlet temperature of 137° C. and a maximum temperature of 195° C. caused by the heat of reaction. Product from the second pass is collected (Example X).

In Example XI, the same catalyst is operated with 2.44 units of hydrogen added per 100 units of benzene. The inlet temperature to the catalyst is 100° C. and the average maximum temperature is 230° C. (Example XI).

The following table sets forth the composition of the products collected in terms of weight percent of product.

Product	IX	X	XI ¹
Total hydrogen units reacted per 100 units benzene	1.27	0.83	2.44
Methylcyclopentane	0.40	0.64	1.44
Cyclohexane	9.33	15.42	18.07
Benzene	69.72	51.31	45.50
Cyclohexylbenzene impurities	0.45	0.62	1.16
Cyclohexylbenzene	15.18	21.17	21.61
Dicyclohexylbenzene impurities	0.12	0.34	0.62
Meta and ortho dicyclohexylbenzene	2.45	4.62	6.81
Para-dicyclohexylbenzene	2.23	5.21	3.96
Tricyclohexylbenzenes	0.08	0.64	0.79

¹ Control.

It is apparent that when this cobalt on rare earth exchanged zeolite catalyst is operated with multiple hydrogen additions and control over the maximum temperature that (a) the ratio of methylcyclopentane to cyclohexane is

reduced (e.g. from 0.08 in Example XI to 0.041 in Example X) (b) the amount of by-products (impurities) boiling close to the cyclohexylbenzene is reduced (e.g. percent of CHB impurities in the CHB fraction is reduced from 5.1 percent in Example XI to 2.9 percent in Example X) and (c) the percent of paradicyclohexylbenzene in the dicyclohexylbenzene fraction is desirably increased (e.g. 35 percent p-DCHB in the DCHB fraction, including impurities, in Example XI versus 51 percent p-DCHB in the DCHB fraction in Example X). It is apparent that the product of Example X would be a preferred stock over the product of Example XI as a feed to a unit for the recovery of para-dicyclohexylbenzene, (d) when the temperature is controlled such as by multiple hydrogen injections, the hydrogen consumption is lowered for the same rate of cyclohexylbenzene formation. The reaction becomes more selective because less C₆ naphthenes are formed.

Clearly products of Examples IX and X prepared by practice of the process of this invention, are superior to the product of control Example XI.

Practice of the process of this invention may be apparent to those skilled in the art from inspection of the process flow sheet set forth in the accompanying schematic drawing and from the following description wherein, as elsewhere in this specification, all parts are parts by weight unless otherwise stated.

In practice of this embodiment of the process of the invention, charge includes fresh benzene admitted through line 10, recycle benzene admitted through line 12 and fresh charge hydrogen admitted through line 13. There may also be admitted through line 15 (although not done in this embodiment) a recycle stream containing orthodicyclohexylbenzene and meta-dicyclohexylbenzene. The charge in line 16, containing 1.27 parts of hydrogen and 100 parts of benzene, may be passed through exchanger 17 wherein it may be heated to 115° C. (239° F.) at 500 p.s.i.g. by heat-exchange medium in line 18.

Hydroalkylation operation 19 contains (like the subsequent hydroalkylation operations) a bed of catalyst containing 22% cobalt on a support, prepared by impregnating, with a solution of cobalt nitrate, a zeolite Y matrix which had been ion-exchanged with a solution of rare earth salt. The catalyst was calcined at 800° C. to yield a product containing 22% cobalt. The catalyst is reduced, prior to use, by contact with flowing hydrogen at 480° C.

Hydrogen is admitted to first hydroalkylation operation 19 in amount of 1.27 parts per 100 parts of benzene, this amount being 60% of the hydroalkylating quantity of hydrogen. As hydroalkylation proceeds at an LHSV of 2, the temperature increases in operation 19 to 205° C. (401° F.). Product from the first hydroalkylation operation in line 20 contains the following:

Components:	Parts
Hydrogen	0
Benzene	69.7
Methylcyclopentane	0.40
Cyclohexane	9.33
Cyclohexylbenzene impurities	0.45
Cyclohexylbenzene	15.18
Dicyclohexylbenzene impurities	0.12
Dicyclohexylbenzene	2.45
(Meta- and ortho-)	2.23
(Para)	0.08
Tricyclohexylbenzenes	0.08

This partial hydroalkylate in line 20 is passed through line 21, to heat exchanger 22, cooled by heat-transfer medium in line 23 to 137° C. (279° F.) and passed through line 24 to second hydroalkylation operation 25. Prior to admission to operation 25, it is mixed with 0.83 parts of hydrogen from line 26. This quantity of hydrogen is 40% of the hydroalkylating quantity of hydrogen. Op-

tionally, if desired, the hydrogen in line 26 may be admitted to the upstream side of heat exchanger 22 so that the hydrogen may aid in cooling the stream in line 20.

As hydroalkylation proceeds in operation 25 at an LHSV of 2, the temperature increases to 195° C. (381° F.). Product from the second hydroalkylation operation in line 27 contains the following:

Components:	Wt. percent
Hydrogen	0
Benzene	51.31
Methyl cyclopentane	0.64
Cyclohexane	15.42
Cyclohexylbenzene impurities	0.62
Cyclohexylbenzene	21.17
Dicyclohexylbenzene impurities	0.34
Dicyclohexylbenzene (Meta- and ortho-)	4.62
(Para)	5.21
Tricyclohexylbenzenes	0.64

It will be apparent that it is unexpected that the high conversion of 21% unexpectedly yields a high-purity cyclohexyl benzene containing only 0.6% of cyclohexylbenzene impurities. (In a comparative example, an attempt to have the same high level of conversion by mixing all the hydrogen (2.44 parts per 100 parts of benzene) with the same total quantity of charge prior to admission to the hydroalkylation operation was unsuccessful. The temperature increased from 100° C. at the inlet to 230° C.; and the product stream undesirably contained 1.16% cyclohexylbenzene impurities. This is unsatisfactory.)

Hydroalkylation product in line 27 is passed to separation operation 28 wherein any trace of light gas may be separated. The separated gases are withdrawn through line 14.

Flashed product liquid is passed through line 29 to heat exchanger 30, heated by steam in line 31, wherein it is heated before being passed to benzene recovery operation 32. Overhead, containing 52.4 parts of benzene, 0.65 parts of methylcyclopentane, and 15.8 parts of cyclohexane, is withdrawn through line 33, condensed in heat exchanger 34 (cooled by water in line 35), and collected in condensate drum 36. A portion of the benzene condensate is returned as pumped reflux through line 37; and the remainder is passed through line 12 to a naphthene removal unit (not shown) to separate methyl cyclopentane and cyclohexane before being recycled to operation 19. If desired, a portion of the condensate may be withdrawn through line 38.

Bottoms in tower 32 are reboiled in heat exchanger 39 by steam in line 40 and returned to tower 32 through line 41. Net bottoms, in amount of 33.3 parts, contain 21.6 parts of cyclohexylbenzene, 0.63 parts of cyclohexylbenzene impurities, and 11 parts of dicyclohexylbenzene and tricyclohexyl benzenes and their impurities.

Net bottoms in line 42 are passed to heat exchanger 43 heated by steam in line 44 wherein they are heated and then passed to cyclohexyl benzene recovery operation 45. Cyclohexylbenzene along with dicyclohexyl and the methylcyclopentylbenzenes are withdrawn as overhead through line 46, condensed in heat exchanger 47 against water in line 48, and collected in collection vessel 49. A portion of the condensate is passed as pumped reflux to tower 45 through line 50. 22.25 parts of overhead, including cyclohexylbenzene are withdrawn through line 51.

Bottoms in tower 45 are reboiled in heat exchanger 52 heated by steam in line 53 and returned to tower 45 through line 54. Net bottoms in line 55, in amount of 11.04 parts, may contain principally ortho-dicyclohexylbenzene and meta-dicyclohexylbenzene (in total amount of 4.72 parts), and 5.32 parts of para-dicyclohexylbenzene. Small amounts (0.35 parts) of other components boiling in the dicyclohexylbenzene range may be present

including higher boiling components typically tricyclohexyl benzenes.

In this preferred embodiment, net bottoms in line 55 are passed through heat exchanger 56 heated by a stream in line 57 and passed to dicyclohexyl benzene recovery operation 58. Bottoms are reboiled in heat exchanger 59 heated by a stream in line 60 and returned to dicyclohexyl benzene recovery tower 58 through line 61. Net bottoms in line 62 may be essentially tricyclohexyl benzenes.

Overhead from tower 58 is withdrawn through line 63, condensed in heat exchanger 64 against water in line 65, and collected in collection vessel 66. The dicyclohexylbenzenes passed to vessel 66 may contain 51.5% of para-dicyclohexylbenzene and 45.5% of ortho-dicyclohexylbenzene and meta-dicyclohexylbenzene.

Pumped reflux is returned through line 67 to tower 58; and 10.4 parts are withdrawn through line 68.

5.2 parts of diluent isopropyl alcohol are admitted through line 69 and the mixture is cooled to minus 10° C. (14° F.) in heat exchanger 70 by refrigerant in line 71.

The cooled mixture of dicyclohexylbenzenes, now primarily a slurry of solid para-isomer in a liquid containing isopropyl alcohol and the meta-isomer, is passed to separation operation 72. Filtration at minus 10° C. (14° F.) permits recovery of 3.8 part of para-dicyclohexylbenzene filter cake (containing 0.2 part of mixed ortho- and meta-isomers). Isopropanol is admitted through line 73 to slurry the filter cake; and the slurry is withdrawn from collector 74 and passed through line 75 at minus 10° C. (14° F.) to filter 76.

Filtrate from filter 76, containing principally isopropanol, is withdrawn through line 77; and filter cake in amount of 4.0 parts is withdrawn from collector 78 through line 79. Para-dicyclohexylbenzene in line 79 may be recovered in amount of 3.8 parts.

Filtrate from filtration operation 72 is withdrawn at minus 10° C. (14° F.) through line 80. This filtrate contains principally meta-dicyclohexylbenzene, ortho-dicyclohexylbenzene, isopropanol, and small amounts of para-dicyclohexylbenzene (1.6 parts) and other impurities (0.3 parts.)

The filtrate in line 80 is passed through heat exchanger 81 heated by steam in line 82, and then passed to isopropanol tower 83. Overhead isopropanol in line 84 may be condensed in heat exchanger 85 (cooled by water in line 86) and collected in vessel 87. A first portion of the condensed isopropanol may be pumped as pumped reflux through line 88 to tower 83. A second portion may be passed through line 89 to line 73. An aliquot of the isopropanol in line 89 may be passed through lines 9— and 69 to line 68. Isopropanol may be added or withdrawn, as necessary, through line 91.

Bottoms from tower 83 may be reboiled in heat exchanger 92 heated by steam in line 93 and returned through line 94 to tower 83. Net bottoms, stripped ortho- and meta-dicyclohexyl benzenes, may be withdrawn through line 95. Ortho- and meta-dicyclohexyl benzenes may be withdrawn from, or added to, the system through line 96. Ortho- and meta-dicyclohexylbenzenes may (after a drying operation not shown) optionally be passed through line 15 to join with the charge dicyclohexyl benzenes in line 11.

The use of this novel process yields hydroalkylation reaction effluent in line 29 which desirably contains substantially decreased proportions of undesirable cyclohexylbenzene impurities (dicyclohexyl and methylcyclopentylbenzenes) and naphthalenes.

Use of the novel process permits hydroalkylation to be carried out with liberation, during hydroalkylation, of much less heat per unit of cyclohexyl benzene formed than is obtained by prior art practice. The means that 75 more throughput can be passed through a reactor; or

that a reactor can be made smaller; or that it can be operated at lower temperatures to give the desired yield; or that it can be operated at the same temperature with higher effective yield.

In the prior art, a limiting determinant on the reaction has been the ability to control heat transfer in the hydroalkylation reactor to keep within desired temperature range and thus minimize formation of undesirable by-products.

The novel process is characterized by the ability to operate under conditions permitting attainment of high concentrations of cyclohexyl benzene (up to e.g. 30%) and to operate with decreased heat liberation due e.g. to decreased formation of exothermically produced dicyclohexyl benzenes.

It is a feature of the process of this invention that when the hydroalkylation is carried out at a lower temperature, the ratio of the para to the meta dicyclohexylbenzenes is increased. The para dicyclohexylbenzene can be readily separated and purified from the mixed dicyclohexylbenzene fraction. Thus to increase para-dicyclohexylbenzene recovery, it is advantageous to operate at low hydroalkylation temperature in order to take advantage of the more favorable isomer ratio in the dicyclohexylbenzene fraction. The percent para DCHB in the DCHB fraction can be increased from about 35% when the maximum temperature is greater than 230° C. to greater than 65% when the maximum reactor temperature is less than 130° C.

By hydroalkylating in stages with multiple additions of hydrogen, the heat liberated can be controlled without excessive temperatures being reached. Thus by avoiding high temperatures more favorable product selectivities are obtained.

Although this invention has been illustrated by reference to specific embodiments, it will be apparent to those skilled in the art that various changes and modifications may be made which clearly fall within the scope of this invention.

We claim:

1. The process for hydroalkylating a charge mono-nuclear aromatic hydrocarbon with a hydroalkylating quantity of hydrogen which comprises

passing said charge hydrocarbon and a first portion of said hydroalkylating quantity of hydrogen through a first hydroalkylation operation at hydroalkylation conditions thereby forming a partially hydroalkylated stream;

withdrawing said partially hydroalkylated stream from said first hydroalkylation operation;

passing said partially hydroalkylated stream through at least one subsequent hydroalkylation operation at hydroalkylation conditions;

passing the remainder of said hydroalkylating quantity of hydrogen to said subsequent hydroalkylation operation;

maintaining said partially hydroalkylated stream during passage into each hydroalkylation operation, at hydroalkylation conditions thereby forming product hydroalkylate; and

said hydroalkylation operations.

withdrawing product hydroalkylate from the last of

2. The process for hydroalkylating a charge mono-nuclear aromatic hydrocarbon as claimed in claim 1 wherein said first portion is 10%-75% of the hydroalkylating quantity of hydrogen.

3. The process for hydroalkylating a charge mono-nuclear aromatic hydrocarbon as claimed in claim 1 wherein said first portion is about 50% of the hydroalkylating quantity of hydrogen.

4. The process for hydroalkylating a charge mono-nuclear aromatic hydrocarbon as claimed in claim 1 wherein substantially the same percentage of the hydroalkylating quantity of hydrogen is added to each of said first hydroalkylation operation and said subsequent hydroalkylation operations.

5. The process for hydroalkylating a charge mono-nuclear aromatic hydrocarbon as claimed in claim 1 wherein hydroalkylation is carried out in two hydroalkylation operations.

6. The process for hydroalkylating a charge mono-nuclear aromatic hydrocarbon as claimed in claim 1 wherein hydroalkylation is carried out in two hydroalkylation operations and 40%-70% of the hydroalkylating quantity of hydrogen is admitted to the first hydroalkylation operation and 30%-60% of the hydroalkylating quantity of hydrogen is admitted to the second hydroalkylation operation.

7. The process for hydroalkylating a charge hydrocarbon aromatic hydrocarbon with a hydroalkylating quantity of hydrogen as claimed in claim 1 wherein the temperature of hydroalkylation is 80° C.-250° C.

8. The process for hydroalkylating a charge hydrocarbon aromatic hydrocarbon with a hydroalkylating quantity of hydrogen as claimed in claim 1 wherein the temperature of hydroalkylation is 100°-210° C.

9. The process for hydroalkylating a charge hydrocarbon aromatic hydrocarbon with a hydroalkylating quantity of hydrogen as claimed in claim 1 wherein the liquid hourly space velocity in each of the hydroalkylation operations is 1-15.

10. The process for hydroalkylating a charge hydrocarbon aromatic hydrocarbon with a hydroalkylating quantity of hydrogen as claimed in claim 1 wherein the partial pressure of hydrogen during hydroalkylation is 100-1500 p.s.i.g.

11. The process for hydroalkylating a charge mono-nuclear aromatic hydrocarbon with a hydroalkylating quantity of hydrogen which comprises:

passing said charge hydrocarbon through a plurality of hydroalkylation operations at hydroalkylation conditions;

passing a portion of said hydroalkylating quantity of hydrogen to each of said hydroalkylating operations; cooling said partially hydroalkylated stream during said hydroalkylation operations; and withdrawing product hydroalkylate from the last of said hydroalkylation operations.

12. The process for hydroalkylating a charge mono-nuclear aromatic hydrocarbon with a hydroalkylating quantity of hydrogen which comprises

passing said charge hydrocarbon through a first and at least one subsequent hydroalkylation operation at hydroalkylation conditions;

passing a portion of said hydroalkylating quantity of hydrogen to each of said hydroalkylating operations;

cooling said partially hydroalkylated stream prior to addition to each of said subsequent hydroalkylation operations; and

withdrawing product hydroalkylate from the last of said hydroalkylation operations.

13. The process for hydroalkylating a charge mono-nuclear aromatic hydrocarbon with a hydroalkylating quantity of hydrogen which comprises:

passing a portion of said hydroalkylating quantity of hydrogen to each of said hydroalkylation operations at hydroalkylation conditions

passing a portion of said hydroalkylating quantity of hydrogen to each of said hydroalkylation operations;

cooling said partially hydroalkylated stream to 80° C.-200° C. prior to admission to each of said subsequent hydroalkylation operations; and

withdrawing product hydroalkylate from the last of said hydroalkylation operations.

14. The process for hydroalkylating benzene with a hydroalkylating quantity of hydrogen which comprises passing said charge benzene and 40%-70% of the hydroalkylating quantity of hydrogen through a first hydroalkylation operation at hydroalkylation condi-

tions including a temperature of 80° C.-200° C. thereby forming a partially hydroalkylated stream; withdrawing said partially hydroalkylated stream from said first hydroalkylation operation cooling said withdrawn partially hydroalkylated product stream to 80° C.-200° C.; 5 passing said cooled stream and 30%-60% of the hydroalkylating quantity of hydrogen to a second hydroalkylation operation at hydroalkylating condition thereby forming a product hydroalkylate; and withdrawing said product hydroalkylate.

UNITED STATES PATENT OFFICE
CERTIFICATE OF CORRECTION

Patent No. 3,784,617 Dated January 8, 1974

Inventor(s) R. M. SUGGITT, J. M. CRONE, JR. AND ALFRED ARKELL

It is certified that error appears in the above-identified patent and that said Letters Patent are hereby corrected as shown below:

Col. 2 Table reads "components" should read component

Col. 6, line 3 "benezne" should read --benzene--

Col. 11, Claim 1
last line

--the last two lines should be reversed
so as to read --withdrawing product
hydroalkylate from the last of said
hydroalkylation operations.--

Signed and sealed this 6th day of August 1974.
